UNITED STATES PATENT OFFICE.

CLAUDE C. VAN NUYS, OF CRANFORD, NEW JERSEY, ASSIGNOR TO AIR REDUCTION COMPANY, INCORPORATED, A CORPORATION OF NEW YORK.

METHOD AND APPARATUS FOR SEPARATING THE CONSTITUENTS OF GASEOUS MIXTURES.

Application filed April 29, 1921. Serial No. 465,518.

To all whom it may concern:

Be it known that I, CLAUDE C. VAN NUYS, a citizen of the United States, residing at Cranford, in the county of Union, State of New Jersey, have invented certain new and useful Improvements in Methods and Apparatus for Separating the Constituents of Gaseous Mixtures; and I do hereby declare the following to be a full, clear, and exact 10 description of the invention, such as will enable others skilled in the art to which it appertains to make and use the same.

This invention relates to the liquefaction and separation of gaseous mixtures having three constituents for the purpose of recovering such constituents in a theoretically and commercially economical manner. The method employed is particularly adaptable for the separation of the constituents of air, 20 although it may be applied for that purpose to any ternary mixture with constituents, the boiling points of which are each different from the others.

It has been proposed heretofore, and commercial methods are now operated, to separate by liquefaction and subsequent rectification, the constituents of a ternary gaseous mixture such as atmospheric air, which for the purpose of this disclosure, is considered to be composed of oxygen, nitrogen and argon, thereby disregarding the minute quantities of rare elements present. Methods as heretofore practiced have, however, relatively low efficiency when compared to the theoretical possibilities. For example, such methods as practiced heretofore employ eight to ten times as much energy as that theoretically required to separate the constituents in substantial purity, and it has been found impossible to actually recover more than one constituent in suitably pure condition. Thus, in all these liquefaction methods for the separation of air, if it is desired to produce substantially pure oxygen, it is found impossible to recover more than 70 to 75% of the oxygen contained in the air treated. For the purpose of increasing the efficiency of air-separation, both from the standpoint of the amount of energy expended and the percentage of recovery of the constituents, an extensive study of the various methods heretofore

practiced has been undertaken with the results hereinafter set forth.

It is the object, therefore, of the invention 55 to eliminate many of the sources of energy loss in methods as heretofore practiced, by avoiding as far as possible all thermodynamically irreversible operations in connection with the production of the refrigerative 60 effect required in the liquefaction cycle, and at the same time, by a rational correlation of the steps of rectification with those employed for the production of the necessary refrigerative effect, to recover all three 65 constituents in substantial purity, without any serious loss in the recovery thereof.

A further object of the invention is the provision of a method of and apparatus for the production of argon from the atmosphere in an economical and efficient manner 70 accompanied by the recovery of oxygen of higher purity than has heretofore been possible in liquefaction operations owing to the difficulty experienced in separating argon 75 therefrom.

Further objects and advantages of the invention will be apparent as it is better understood by reference to the following specification and accompanying drawing diagrammatically illustrating an apparatus 80 which is adapted for use in practicing the invention. It is to be understood that in the drawing no attempt has been made to illustrate those details of liquefaction apparatus 85 which are well known to those skilled in the art, the purpose of the drawing being merely to assist the reader to a complete comprehension of the essential features of the invention. 90

A distinguishing feature of the invention is the separation of the three constituents in three successive steps, each one of these steps employing ordinary processes of separation. 95

The first step consists in separating all the air to be treated into two parts by means of selectively liquefying a portion of it, employing for that purpose to the greatest possible degree, the well known method of 100 "backward return." This step results in the separation of a fraction, consisting approximately of half by volume of the air treated, and composed of substantially pure gaseous

nitrogen, the other portion being a ternary mixture of nitrogen, oxygen and argon in liquid condition, the percentages of the two latter constituents being substantially greater than for atmospheric air, e. g., oxygen 45%, argon 2% and nitrogen 53%. The pure nitrogen fraction, which is available at substantially the original pressure of the compressor, is not further treated, but after 10 being brought into contact with succeeding portions of the incoming air, is employed as a working fluid in an expansion engine, or motor, whereby it attains an extremely low temperature, the refrigerative effect of 15 which is applied in an efficient manner to the liquefaction cycle.

The second step of the separation consists in separating by a suitable rectification the portion enriched in oxygen and argon into 20 two sub-portions, one of which is gaseous and has a composition approximating that of the original air, except that it is somewhat enriched in argon, while the other contains from 93 to 95% oxygen and approximately half of the argon contained in 25 the original air. The sub-portion of approximate air composition is brought into contact by means of suitable interchangers with the incoming air in order to cool the 30 air, and is thereby restored to substantially the original air temperature. It is then either returned directly to the main air compressor, or in case the operation is such that it has sufficient pressure, it is expanded in 35 an engine or motor, and after assisting to cool the incoming air, it is returned to the air compressor and thence back to the liquefaction cycle.

The sub-portion of 93 to 95% oxygen is 40 available in the liquid state according to the method herein described and is delivered to an intermediate point of an auxiliary rectification column, in which the third and last step of the separation process is accomplished, this consisting in the production of oxygen of high purity in a liquid condition, and an argon product containing a small amount of oxygen and only a very minute quantity, if any at all, of nitrogen. A small 45 amount of substantially pure nitrogen is also separated in this step, which is returned at a suitable level to the primary rectification column by means of which the second separation is accomplished.

50 In order that the various advantages of this method may be pointed out and comparisons made with methods heretofore practiced, reference is made to a well-known method, which has been in extensive commercial use for the production of oxygen and argon from atmospheric air. In the latter method, atmospheric air is compressed to a pressure of substantially 30 atmospheres in a two or three stage compressor provided 55 with inter-coolers and after-coolers supplied

with water, and is thereafter cooled in interchangers by indirect contact with gases resulting from the separation. A portion of the cooled air is conveyed to a liquefier where it is further cooled and liquefied in toto, i. e., non-selectively, by indirect contact with the cooled separated gases before the latter pass to the interchanges. The liquid air thus produced is intended to compensate for losses of liquid in the rectification columns and condensers due to external heat leakages into the liquefaction cycle. The other portion of the cooled air is conveyed to an expansion engine, where it is further cooled by expansion with external work to a pressure of 4 to 5 atmospheres. It then passes into a pot at the base of the primary rectification column, and thence upward through tubes of a "backward return" condenser, and is therein selectively liquefied by indirect contact with liquid oxygen resulting from rectification as hereinafter described, the latter being evaporated around the tubes at a somewhat lower pressure than that of the air in the tubes.

The result of this selective liquefaction of the engine exhaust is to separate it into two portions, one of which consists of substantially pure nitrogen, which is subsequently liquefied by indirect contact with evaporating liquid at a higher level in the rectification column, while the other consists of a liquid of substantially 45 to 47% oxygen purity. The liquid air produced in the liquefier is added to the enriched liquid and the combined liquid is conveyed upwardly through a pipe having a pressure-reducing valve and is discharged into the rectification compartment of the main column where it cascades over rectification trays of the usual form. The liquid nitrogen produced as just described, is conveyed through a similar pipe and pressure-reducing valve into the rectification column at a point near the top.

Liquid oxygen of 95 to 97% purity collects at the bottom of the primary rectification column. Nitrogen containing substantial amounts of oxygen escapes at the top of the column, and after passing through the liquefier and temperature exchangers in order to cool the incoming air, is rejected. In the actual operation of the method here referred to, this waste nitrogen carries from 5 to 8% oxygen and over half of the argon contained in the air treated.

The 95 to 97% liquid oxygen which collects at the bottom of the primary rectification column is led through a pipe and delivered in the liquid state to an intermediate point of an auxiliary rectification column, in which it cascades over rectification trays of the usual form, and thereby has its oxygen percentage increased still further by contact with vapors ascending in said column.

As the high purity oxygen liquid collects at the bottom of the auxiliary column, it is vaporized by coming into indirect contact with low purity vapors contained in the 5 tubes of the condenser portion of the auxiliary column, these vapors being the effluent from the top of the auxiliary column after compression in an auxiliary compressor subsequent to circulating in heat exchanging 10 relation with the compressed gas delivered by that auxiliary gas compressor. The compressed gas, after passing from the compressor through the interchanger just described, is delivered to a pot at the base of 15 the auxiliary column and thence passes upward through tubes of the auxiliary condenser, being selectively liquefied therein, a small amount of substantially pure nitrogen being abstracted from the top of the tubes 20 and delivered to a suitable level in the main rectification column.

The liquid produced in the tubes of the auxiliary condenser collects in the bottom of the pot just described and passes upward 25 through a pipe and pressure reducing valve and is delivered to the top tray of the auxiliary rectification column, where it serves as a "reflux" liquid for the vapors rising above the admission level of the oxygen liquid coming 30 from the primary rectification column as already described.

When a suitable purity of argon product is attained in the auxiliary compressor cycle just described, limited quantities of this 35 product are abstracted from the auxiliary cycle at the point of entrance of the gases to the auxiliary compressor, and conducted to a suitable holder or container. The high purity liquid oxygen evaporated from 40 around the tubes of the auxiliary condenser, and constituting the oxygen product, is conducted back through the liquefier and interchanger of the primary column, and thence to a suitable gasometer or container.

It is evident from the foregoing description that since the liquid product of the primary column, leaves that column in the liquid state, an equivalent amount of liquid must be returned to it and this liquid must 50 be derived either directly or indirectly from the auxiliary column. If this precaution were not taken, there would be a constant accumulation of liquid in the auxiliary column, making operation thereof impossible. 55 The primary column, by reason of the presence of the auxiliary cycle, must also receive a sufficient amount of liquid air from the primary column "liquefier" as a make-up liquid to compensate for the inleakage of 60 external heat to the auxiliary cycle. In the commercial method here referred to, the liquid necessary to be returned from the auxiliary to the primary column is derived indirectly from the auxiliary column by evaporating 65 the excess liquid therein by means of

a vaporizing coil, which is located in the lower liquid reservoir of the auxiliary column and in which unseparated air circulates, being non-selectively liquefied more or less completely therein. This unseparated air is 70 obtained by dividing the exhaust air leaving the expansion engine into two portions, one of which goes direct to the tubular condenser of the primary column as already described, while the other portion is conducted 75 through the vaporizing coil of the auxiliary column as just stated. This portion of the engine exhaust evaporates the excess liquid of the auxiliary column, and after complete or partial non-selective liquefaction, passes 80 to an upper level of the primary rectification column, where it is mixed with the descending liquid derived from the tubes of the primary condenser and from the liquid coming from the liquefier.

It is thus apparent that the operation of the auxiliary column requires a greater amount of air to be diverted to the liquefier than would be necessary if the auxiliary cycle were absent, thus reducing the amount 90 passing to the expansion engine, and furthermore, requires a diverting of a substantial portion of the expansion engine exhaust to the vaporizing coil of the auxiliary column. The only portion of air which is 95 selectively liquefied by "backward return" is that portion which passes direct from the expansion engine exhaust to the main tubular condenser. The operation of the auxiliary column thus very much reduces the 100 amount of pure nitrogen liquid available for "reflux" liquid at the top of the primary rectification column, and it is found that the liquid nitrogen available for that purpose is much too small for the requirements. This condition tends to be aggravated in the operation of this method by reason of the fact that it is difficult to insure that all of that portion of the engine 105 exhaust passing through the vaporizing coil in the auxiliary condenser is liquefied in that coil, since in order to make the boiling effect of the coil sufficiently vigorous there is a strong tendency on the part of the operator to open the valve controlling the 110 flow through this coil to a point where vapor, as well as liquid, leaves said coil to be delivered to the primary column rectifier. The presence of this vapor requires an increased amount of "reflux" nitrogen liquid 115 in order to prevent the escape of substantial amounts of oxygen in the effluent gas from the primary column, and, at the same time, makes it necessary to exercise very much greater care in the operation of the primary 120 rectification in order to secure a constancy of composition of the oxygen product and to prevent very serious losses of oxygen and argon from the top of the main rectification 125 column.

All these difficulties, as I have described them, arising from the operation of the auxiliary column, contribute to the low efficiency of recovery attained in the operation of the commercial method under consideration. The most serious cause, however, of the low efficiency is the fact that the attempt is made to separate in one operation and in a single rectification column substantially all the nitrogen contained in the air treated. It is impossible, however, to obtain at the top of the primary rectification column substantially pure nitrogen and at the same time an oxygen-argon product of sufficiently low nitrogen content to be successfully treated in the auxiliary condenser and rectification column.

Furthermore, it has been found to be impossible to efficiently produce oxygen of high purity, and, at the same time, argon of the desired purity by the earlier method. This result is doubtless due to the failure to balance all of the factors effecting the operation, a result which has been achieved, however, in the method hereinafter described.

In the operation of the method which forms the subject of the invention, only a portion of the gaseous mixture treated is liquefied and the liquefaction is accomplished at the initial pressure, i. e., as delivered by the compressor. Approximately 52% of the original air passes through the apparatus unliquefied and this fraction consists of substantially pure nitrogen and is available at the original pressure. The major portion of the refrigerative effect necessary in the whole apparatus is derived from this high pressure nitrogen by expanding it with external work in a suitable motor or engine after it has been brought into heat exchanging relation with the incoming mixture. This expansion engine operates continuously between the main compressor pressure and an exhaust pressure only enough greater than one atmosphere to cause the expanded nitrogen to flow through the subsequent liquefier and inter-changers. The exhaust nitrogen is conducted first through a liquefying compartment forming an extension of the "backward return" condenser at the base of the primary column and located at the lower end of that condenser. The effect of this cold exhaust nitrogen is to liquefy a sufficient amount of the unseparated mixture ascending in the tubes of the condenser to compensate for losses of liquid in the primary and auxiliary condensers and rectifiers due to inleakage of external heat therein, and this liquefaction is accomplished selectively.

It is thus possible to avoid reducing the maximum enrichment in oxygen and argon obtainable by the principle of "backward return," inasmuch as no liquid unenriched in oxygen is added to the liquid derived from

the tubes of the "backward return" condenser, and it is also possible to obtain the maximum amount of high pressure nitrogen from the upper end of said condenser. The liquid obtained in the tubes of said condenser, aside from that produced by the engine exhaust passing through the liquefier just described, is obtained as a result of the vaporization of liquids surrounding said tubes. For this purpose, two liquids are employed contained in separate compartments, one above the other. One of these is the 93-95% oxygen liquid which descends to the bottom of the main rectification column and collects around the tubes of the "backward return" condenser, and the other is liquid returning from the auxiliary column as hereinafter described. The primary rectification column receives at its upper end the enriched oxygen liquid produced inside the tubes of the "backward return" condenser after its pressure has been reduced by an expansion valve located in the pipe through which it passes. The vapor leaving the tube of the column will have an oxygen content approximating that of the vapor having phase equilibrium with a liquid with an oxygen content of 45-46% and will thus approximate the composition of the original unseparated mixture. This effluent, after giving up its cold to the incoming mixture, is "cycled" back to the main compressor and thus re-enters the liquefaction cycle.

If air is treated, this effluent will be totally free from such substances as moisture and carbondioxide, which must be removed from atmospheric air previous to successful liquefaction and separation thereof at considerable trouble and expense, and thus an important economy is accomplished compared with methods which reject in the "waste" gases the portion of air passing through the apparatus unseparated. The amount of unseparated air thus returning to the compressor is found to be from 30 to 35% by volume of the air entering the compressor directly from the atmosphere, and this procedure thus totally avoids the serious losses of oxygen and argon in the effluent gases leaving the rectification column, which are experienced in commercial methods as heretofore practiced. The 93-95% oxygen liquid produced at the base of the primary rectification column passes through a pipe and pressure reducing valve and enters the auxiliary rectification column at an intermediate level.

The operation of the auxiliary condenser and rectifier is similar to that in the commercial method described above, except for the return from the auxiliary to the primary rectification column of the liquid equivalent of that passing from the primary column to the auxiliary. This liquid equivalent, instead of being derived indirectly from the

excess liquid accumulating in the auxiliary column, is obtained directly and automatically from the auxiliary column by placing the latter at such a level with respect to the 5 primary rectification column, that when the liquid at the base of the auxiliary column reaches a predetermined level, it automatically overflows into a liquid pipe passing horizontally from the auxiliary column to 10 the primary rectification column. This pipe enters a special compartment surrounding the tubes of the primary "backward return" condenser located between the liquefier compartment thereof already described and the 15 compartment containing the 93-95% oxygen liquid. Since the liquid flowing through this pipe is derived from the base of the auxiliary column, it will be substantially pure oxygen and the pressure thereof will 20 be somewhat lower than that of the liquid collecting at the bottom of the primary rectification column. It will thus readily evaporate by indirect contact with the ascending vapors inside the tubes of the primary condenser; and thus vaporization will be automatic, since only the excess liquid from the auxiliary column returns to the main column. The pipe carrying this liquid, since it 25 passes directly from one column to the other, can be made very short, and it will not be necessary to provide in it any regulating valve for controlling the flow through it. The flow of liquid therein, being automatic, will not require any attention from the operator, and the arrangement also avoids any 30 heat leakage due to the presence of a valve requiring frequent adjustment. The liquid oxygen evaporating in the special compartment of the primary "backward return" 35 condenser as described constitutes the oxygen product of the separation, and after being conducted back to heat exchanging relation with the incoming mixture, is fed directly to a gasometer or a balloon.

40 The argon product is derived from the auxiliary compressor cycle in a manner similar to that employed in the commercial method already described. The only points in the cycle herein described at which argon can escape, other than at the proper outlet, is 45 from the top of the primary "backward return" condenser, i. e., with the high pressure nitrogen or with the oxygen produced by the method.

50 The refrigerative effect available in the method, as I have described it, by reason of the relatively large quantities of high pressure nitrogen leaving the top of the main condenser, will be considerably in excess of that necessary to keep the cycle in operation. This excess of available energy may be utilized in various ways; for example, we may divert a portion of the engine exhaust for the purpose of precooling the atmospheric 55 air entering the compressor, as is disclosed

in the application of Claude C. Van Nuys, Serial No. 453,577, or external heat may be added to this high pressure nitrogen and the latter then employed as a working substance in an auxiliary expansion motor or engine 70 for the recovery of power.

Referring to the drawing, 5 indicates the primary column which is divided by a plurality of partitions 6, 7, 8 and 9, into a lower rectifying compartment 10, a chamber 11 for 75 cold gaseous products which circulate about the baffles 12 therein, a liquid chamber 13, another chamber 14, and an upper rectifying compartment 15. The purposes and functions of these several compartments, will 80 more clearly appear as the description proceeds.

The gaseous mixture undergoing liquefaction is delivered through a pipe 16 to the compartment 10 beneath a plurality of trays 85 17 therein, and proceeds upwardly through the trays in direct contact with liquid descending thereover, which liquid is enriched by contact with the gaseous mixture in the least volatile constituent of the mixture, 90 while the most volatile constituent is separated therefrom and travels upwardly with the gaseous mixture. The liquid accumulates in the bottom of the column and the gaseous mixture travels upwardly through 95 tubes 18 in indirect contact first with cold gaseous products in the chamber 11, then with liquid in the chamber 13 and finally with liquid in the chamber 14 and receptacle 19 disposed therein. The gaseous mixture thus traveling through the tubes is progressively cooled and selectively liquefied, that is to say, the least volatile constituent, namely oxygen in case air is treated, together with practically all of the argon and 100 some nitrogen becomes liquid and descends in the tubes in contact with the incoming gaseous mixture under the well-known principle of "backward return" whereby the liquid is progressively enriched in the least volatile constituents, while the residual gas is substantially pure nitrogen when it is finally delivered to a head 20 in which the tubes 18 terminate. This residual gas is delivered 105 through a pipe 21 from the column at substantially the initial pressure at which the gaseous mixture was introduced to the column.

The liquid descending in the tubes 18 is 110 delivered to the chamber 10 and passes over the trays 17 in contact with the gas entering through the pipe 16. The liquid is partially rectified and further enriched in the less volatile constituents, while the most volatile constituent escapes therefrom and travels 115 upwardly with the gas into the tubes 18. The liquid finally accumulates in the bottom of the column and is delivered through a pipe 22 having a pressure-reducing valve 23 to the top of the rectifying compartment 15. 120 125 130

In this compartment, the liquid flows downwardly over the trays 24 in direct contact with vapors arising from the liquid in the chamber 14, and receptacle 19 which is undergoing vaporization by heat interchange with the gas in the tubes 18. Rectification of the liquid is thus carried on with gradual enrichment thereof in the less volatile constituents, the most volatile constituent being transferred therefrom to the vapors arising through the trays. The liquid is delivered through a pipe 25 to the receptacle 19 through which it overflows into the chamber 14, while the effluent gaseous mixture, which in case air is being treated, contains nitrogen, oxygen and argon, is delivered from the column through a pipe 26.

As previously noted, the liquid accumulating in the chamber 14 consists of oxygen in case air is treated with a considerable proportion of the argon present in the atmosphere and some nitrogen, and it is desired to further separate these elements for the purpose of recovering substantially pure oxygen and a gas which is materially enriched in argon or which may be practically pure argon. For this purpose, it is necessary to subject the liquid to an auxiliary rectification, and, for this purpose, the liquid is led through a pipe 27 controlled by a valve 28 to an auxiliary column 29, which is divided by partitions 30, 31 and 32 into a chamber 33, a compartment 34 for the liquid product of the operation, a chamber 35 for the accumulation of liquid, and a rectifying compartment 36. The liquid from the pipe 27 is delivered to trays 37 in the compartment 36 and flows downwardly thereover in direct contact with vapors from liquid which accumulates in the chamber 35, thus causing enrichment of the liquid in the least volatile constituent, for example, oxygen; while nitrogen and argon for example, pass upwardly with the vapors through the trays. The effluent mixture containing nitrogen, argon and oxygen, for example, escapes through a pipe 38 and is delivered to an exchanger 39, where it gives up its cold to preceding portions of the same gaseous mixture after the latter has been compressed in a compressor 40 to which the gas is delivered from the exchanger 39 through a pipe 41. The compressed gas is returned to the exchanger through a pipe 42 and circulates about baffles 43 therein and around the tubes 44 which carry the cold effluent mixture from the column 29. The compressed gaseous mixture thus cooled is delivered through a pipe 45 to the chamber 33 at the bottom of the column 29 and passes thence upwardly through tubes 46 in indirect contact with liquid in the compartment 34 and chamber 35. In the tubes, the gaseous mixture is liquefied partially under the principle of "backward return," the liquid returning to

the chamber 33 while the residual unliquefied gas is delivered to a head 47. This residual gas in the case under consideration is substantially pure nitrogen and is withdrawn through a pipe 48, controlled by a valve 49 and delivered to the upper portion of the rectifying compartment 15 in the primary column, whence it escapes with the other vapors in the compartment through the pipe 26. 75

The liquid accumulating in the bottom of the column 29 is delivered through a pipe 50 having a pressure-reducing valve 51 to the top of the rectifying compartment 36 and flows downwardly over the trays 37 therein, 80 eventually mixing with the liquid delivered to the auxiliary column through the pipe 27. It will be noted that the liquid delivered to the rectifying compartment through the pipe 50 has already passed through the column 85 and has been subjected to recompression and liquefaction to separate further quantities of the most volatile constituent which escapes as the residual gas. This liquid will in the course of operation become substantially enriched in oxygen, while more and more argon accumulates in the gaseous effluent from the auxiliary column which is recompressed and returned to the column. When enrichment in argon has reached the desired point, a 90 portion of the gas may be withdrawn from time to time through a pipe 52, controlled by a valve 53, and delivered to a gasometer 54 or other means of storing the gas. The substantially pure oxygen liquid is delivered 100 through a siphon tube 55 from the chamber 35 to the compartment 34, where a portion of it is vaporized by heat interchange with the gaseous mixture passing up through the tubes 46. Under certain conditions, this 105 vapor may pass up through a tube 56, the end of which is sealed under the liquid in the chamber 35.

It is desired, however, to return the major portion of the pure oxygen liquid accumulating in the compartment 34 to the primary column in order that the low temperature requisite to the operation of this column may be suitably maintained without resort to the expedient herein before referred to, of liquefying the incoming gaseous mixture in a coil disposed in the auxiliary column. A pipe 57 is therefore provided to connect the compartment 34 with the chamber 13 in the primary column. The 110 end of the pipe 57 is disposed near the bottom of the compartment 34 so that the liquid forced over into the primary column when the predetermined level is reached in the auxiliary column is oxygen of substantial purity, 115 which is one of the products of the operation. The liquid which is thus supplied to the chamber 13 of the primary column is evaporated therein by indirect contact with the gaseous mixture passing through the 120 125 130

tubes 18 and is delivered therefrom through a pipe 58 controlled by a valve 59. A branch 60 of the pipe 58 which is controlled by a valve 61 communicates with the compartment 34 of the auxiliary column so that a portion of the vapor formed in that chamber may be withdrawn if desired to supplement the oxygen delivered from the chamber 13. A by-pass 62 controlled by a valve 63 connects the chamber 14 of the column to the pipe 58, the valve 63 being closed in the normal operation of the apparatus but opened in starting the apparatus when the auxiliary column is inoperative, the valves 28, 59 and 61 being closed under these conditions, so that no liquid is delivered to the auxiliary column and no products are withdrawn therefrom.

The several products delivered from the apparatus, that is to say, the residual gas in the pipe 21, the effluent mixture in the pipe 26, and the product delivered through the pipe 58 each leave the columns in relatively cold condition and it is essential to preserve this cold in order to efficiently maintain the desired operation. Consequently, an exchanger is provided, consisting of sections A and B, each provided with a plurality of tubes 64 and 65 about which the incoming mixture compressed in a compressor 66 and conveyed to the section A through a pipe 67 is forced to circulate by baffles 68. The two sections of the exchanger are joined by a pipe 69 to which a purge or drain 70 controlled by a valve 71 is connected.

The effluent gaseous mixture in the pipe 26 is delivered to a chamber 72 at the end of the section B of the exchanger and travels thence through tubes 65 to a chamber 73 at the opposite end of the section, thence through a pipe 74 to a chamber 75 at the end of the section A of the exchanger. In the section A, the gas travels through tubes 65 to a chamber 76 from which it is withdrawn through a pipe 77 controlled by a valve 78 and delivered to an expansion engine 79 where the gas is expanded with external work and thereby materially cooled. The cold expanded product is delivered by a pipe 80 to a chamber 81 at the end of the section A of the exchanger and thence passes through tubes 64 to a chamber 82 at the other end of the exchanger.

It will be recalled that this gaseous effluent contains in the case of the treatment of air, nitrogen, oxygen and some of the argon originally present in the air treated. This material is dry and free from carbon-dioxide, and consequently is in condition for further treatment in the column. It is therefore delivered through a pipe 83 to an inlet 84 of the compressor 66 and mixes with the incoming gaseous mixture such as air which is constantly drawn into the compressor for treatment.

The residual gas or nitrogen delivered from the primary column through the pipe 21 enters a compartment 85 at one end of the section B of the exchanger and passes thence through tubes 64 to a compartment 86 at the opposite end of the section, thereby giving up a portion of its cold to the incoming gaseous mixture. This residual gas amounts to more than substantially 50% by volume of the original mixture and is, under the conditions hereinbefore specified, delivered at substantially the pressure to which the original mixture is subjected before it enters the primary column. Consequently, after being warmed in the section B of the exchanger, it is delivered from the chamber 86 to a pipe 87 controlled by a valve 88 to an expansion engine 89 where it is expanded and thereby cooled, the work thus developed being capable of application for any suitable purpose as for example, compression of further quantities of the gaseous mixture in the system. The cold expanded residual gas is delivered through a pipe 90 to the chamber 11 of the primary column where it serves to cool and liquefy the gaseous mixture traveling through the tubes 18. After passing about the baffles 12 in the chamber, the residual gas is delivered by a pipe 91 to a chamber 92 at one end of the section B of the exchanger and travels through tubes 65 to a chamber 93 at the opposite end of the section, thence through a pipe 94 to a chamber 95 at one end of the section A of the exchanger, thence through tubes 65 to a chamber 96 at the opposite ends of the section A of the exchanger through which it escapes through a pipe 97. The residual gas may be stored for any suitable purpose or discharged to the atmosphere.

The gaseous product, for example substantially pure oxygen, is delivered through the pipe 58 to a chamber 98 at one end of the section B of the exchanger and travels thence through tubes 65 to a chamber 99 at the opposite end of the section of the exchanger, thence through a pipe 100 to a chamber 101 at one end of the section A of the exchanger, thence through tubes 65 to a chamber 102 at the opposite end of the section of the exchanger. The gas is then delivered through a pipe 103 controlled by a valve 104 to a suitable container in which it is stored for subsequent use.

From the foregoing, it will be noted that the features which have been hereinbefore pointed out as distinguishing the method which forms the subject matter of the present invention from the prior art are necessarily employed in the apparatus as illustrated in the drawing and described herein. As a result of operation in the manner described, it is possible to produce and deliver from the apparatus substantially pure oxygen, for example pure nitrogen and a

gaseous mixture principally consisting of argon and oxygen, the argon approaching substantial purity. Furthermore, the operation is exceedingly economical because of the elimination of many of the defects which characterize methods heretofore employed, and of the provision for the recovery of energy expended in compressing the original gaseous mixture.

10 Obviously, although the invention is more particularly designed for the purpose of recovery of nitrogen, oxygen and argon from the atmosphere, it may be employed in analyzing ternary gaseous mixtures, the constituents of which have different boiling points. When applied in the manner and for the purpose described, the method is readily controlled and requires much less attention and supervision than methods hereinbefore used.

15 Various changes may be made in the details of the operations hereinbefore described and in the apparatus employed without departing from the invention or sacrificing 20 any of its material advantages.

I claim:

1. A method of analyzing ternary gaseous mixtures, which comprises separating one of the constituents by a primary liquefaction 30 and rectification operation, thereby providing a liquid consisting substantially of the remaining constituents, separating the latter constituents by an auxiliary rectification operation, and returning one of the constituents in liquid form to assist in maintaining the necessary low temperature in the primary operation.

2. A method of analyzing ternary gaseous mixtures, which comprises separating one of the constituents by a primary liquefaction and rectification operation, thereby providing a liquid consisting substantially of the remaining constituents, separating the latter constituents by an auxiliary rectification operation into a gaseous product enriched in one of the constituents and a liquid consisting of the other constituent in a substantially pure condition, withdrawing the gaseous product and returning the liquid to 50 assist in maintaining the necessary low temperature in the primary operation.

3. A method of analyzing ternary gaseous mixtures, which comprises separating one of the constituents by a primary liquefaction and rectification operation, thereby providing a liquid consisting substantially of the remaining constituents, separating the latter constituents by an auxiliary rectification operation, including recompression and liquefaction of the gaseous effluent from the auxiliary rectification and further rectification of the liquid formed, and returning the liquid product of the auxiliary rectification to assist in maintaining the necessary low temperature in the primary operation.

4. A method of analyzing ternary gaseous mixtures, which comprises separating one of the constituents by a primary liquefaction and rectification operation, thereby providing a liquid consisting substantially of the remaining constituents with a proportion of the first-mentioned constituent as impurity, separating the constituents of the liquid by an auxiliary rectification operation, including recompression and liquefaction of the gaseous effluent from the auxiliary rectification with separation of the constituent constituting the impurity as a residual gas, and further rectification of the liquid formed, and returning the liquid product of the auxiliary rectification to assist in maintaining the necessary low temperature in the primary operation.

5. A method of analyzing ternary gaseous mixtures, which comprises separating one of the constituents by a primary liquefaction operation as a residual gas, subjecting the resulting liquid to a primary rectification operation to separate substantially the remainder of the first-mentioned constituent, thereby providing a liquid consisting substantially of the remaining constituents, separating the latter constituents by an auxiliary rectification operation, and returning one of the constituents in liquid form to assist in maintaining the necessary low temperature in the primary liquefaction operation.

6. A method of analyzing ternary gaseous mixtures, which comprises separating one of the constituents by a primary liquefaction operation as a residual gas, subjecting the resulting liquid to a primary rectification operation to separate substantially the remainder of the first-mentioned constituent together with proportions of the other constituents in an effluent gaseous mixture, thereby providing a liquid consisting substantially of the remaining constituents, separating the latter constituents by an auxiliary rectification operation, returning one of the constituents in liquid form to assist in maintaining the necessary low temperature in the primary liquefaction operation, and returning the effluent mixture for further separation.

7. A method of analyzing ternary gaseous mixtures, which comprises producing therefrom, by a primary liquefaction and rectification operation, a liquid consisting principally of the least volatile constituent, subjecting the liquid to an auxiliary rectification, recompressing and reliquefying the gaseous effluent from this rectification, utilizing the liquid in the auxiliary rectification, and returning the liquid product of this rectification to assist in maintaining the necessary low temperature in the primary operation.

8. A method of analyzing ternary gaseous

- mixtures, which comprises producing a liquid, by a primary liquefaction and rectification operation, consisting of the least volatile constituent with proportions of the remaining constituents, subjecting this liquid to continuing rectification with recompression and reliquefaction of the gaseous effluent therefrom, and returning the liquid product of the auxiliary rectification to assist in maintaining the necessary low temperature in the primary operation.
9. A method of analyzing ternary gaseous mixtures, which comprises producing a liquid consisting principally of the least volatile constituent with proportions of the other constituents, subjecting this liquid to rectification; thereby producing a liquid rich in the least volatile constituent and a gaseous fraction, compressing this gaseous fraction, cooling it to separate a residual gas consisting of the most volatile constituent and a liquid containing chiefly two of said constituents, returning this liquid for further rectification, and withdrawing the liquid product of the rectification and utilizing it in producing the first-named liquid containing the least volatile constituent by selective liquefaction of the gaseous mixture.
10. A method of analyzing ternary gaseous mixtures, which comprises producing by a primary liquefaction and rectification operation a liquid rich in the least volatile constituent and containing other constituents, subjecting this liquid to an auxiliary rectification, returning the liquid product of this rectification to the primary operation, and subjecting the effluent from the auxiliary rectification to recompression and reliquefaction and further rectification.
11. A method of analyzing ternary gaseous mixtures, which comprises producing by a primary liquefaction operation a liquid rich in the least volatile constituent and containing a proportion of the remaining constituents, subjecting this liquid to continuing rectification with recompression and refrigeration of the gaseous effluent to separate a liquid consisting substantially of the least volatile constituent and a residual gaseous product containing another constituent, the gaseous effluent being thereby progressively enriched in a third constituent, and returning the liquid product of the auxiliary operation to the primary operation.
12. A method of analyzing ternary gaseous mixtures, which comprises producing by a primary liquefaction operation a liquid consisting principally of the least volatile constituent with a proportion of the remaining constituents, subjecting this liquid to a continuing rectification with recompression and refrigeration of the gaseous effluent to separate a liquid containing one of said constituents in substantial purity and a residual gaseous product containing another constituent, the gaseous effluent being thereby progressively enriched with a third constituent, withdrawing portions of the gaseous effluent when it is sufficiently enriched, and returning the liquid product of the auxiliary operation to the primary operation.
13. A method of recovering argon, oxygen and nitrogen from the atmosphere, which comprises producing a liquid by a primary liquefaction operation which consists principally of oxygen with proportions of argon and nitrogen, the major portion of the nitrogen being removed in gaseous form during the operation, subjecting this liquid to an auxiliary rectification, thereby producing a liquid consisting of substantially pure oxygen and a gaseous fraction including argon and nitrogen, and returning the liquid oxygen to the primary operation.
14. A method of recovering argon, oxygen and nitrogen from the atmosphere, which comprises producing a liquid by a primary liquefaction operation which consists principally of oxygen with proportions of argon and nitrogen, the major portion of the nitrogen being removed in gaseous form during the operation, subjecting this liquid to an auxiliary rectification, thereby producing a liquid consisting of substantially pure oxygen and a gaseous fraction including argon and nitrogen, returning a portion of the liquid oxygen to the primary operation, compressing the gaseous fraction, subjecting it to indirect contact with the liquid oxygen, thereby liquefying a portion of the gaseous fraction, leaving a residual gaseous product, consisting principally of nitrogen and a liquid fraction including argon, returning the liquid fraction for further rectification and withdrawing portions of the gaseous fraction when it is sufficiently enriched in argon.
15. A method of recovering argon from air, which comprises producing a liquid containing oxygen, nitrogen and argon by a primary liquefaction operation, subjecting the liquid to continuing rectification, compressing the gaseous effluent, cooling it to separate a liquid containing chiefly argon and oxygen and a residue containing practically all of the nitrogen, using the last named liquid in the rectification, and returning the liquid product of the rectification to the primary operation.
16. A method of recovering argon from air, which comprises producing a liquid containing oxygen, argon and nitrogen by a primary liquefaction operation, subjecting the liquid to continuing rectification, compressing the gaseous effluent, cooling it to separate a liquid containing chiefly argon and oxygen and a residue containing substantially all of the nitrogen, using the last

mentioned liquid in the rectification, withdrawing portions of the gaseous effluent when it is sufficiently enriched in argon, and returning the liquid product of the auxiliary rectification to the primary operation.

17. A method of analyzing ternary gaseous mixtures, which comprises separating one of the constituents by a primary liquefaction operation, thereby producing a liquid consisting principally of the remaining constituents, expanding the first mentioned constituent, utilizing the cold thus developed to assist in maintaining the necessary low temperature in the primary operation by passing the expanded constituent in indirect contact with the gaseous mixture undergoing liquefaction, further separating the constituents of the liquid by rectification into a liquid product consisting of another constituent in substantially pure condition and a gaseous fraction consisting principally of the third constituent, withdrawing the liquid product and utilizing it to selectively liquefy the gaseous mixture in the primary operation.

18. A method of analyzing ternary gaseous mixtures, which comprises separating one of the constituents by a primary liquefaction operation, thereby producing a liquid consisting principally of the remaining constituents, expanding the first mentioned constituent, utilizing the cold thus developed to assist in maintaining the necessary low temperature in the primary operation, further separating the constituents of the liquid by rectification into a liquid product consisting of another constituent in substantially pure condition and a gaseous fraction consisting principally of the third constituent, and returning the liquid product to assist in maintaining the necessary low temperature in the primary operation.

19. A method of analyzing ternary gaseous mixtures to recover the constituents thereof in substantial purity, which comprises separating one of the constituents as a residual gas by a primary liquefaction operation with "backward return" of the liquid formed, rectifying the liquid in the primary operation to produce a liquid enriched in another constituent and an effluent gaseous mixture, recompressing and returning the gaseous mixture for further liquefaction in the primary operation, subjecting the liquid produced in the primary operation to an auxiliary rectification to separate a liquid product consisting of the principal constituent thereof, and withdrawing a gaseous product from the auxiliary rectification consisting principally of the third constituent.

20. A method of analyzing ternary gaseous mixtures to recover the constituents thereof in substantial purity, which com-

prises separating one of the constituents as a residual gas by a primary liquefaction operation with "backward return" of the liquid formed, rectifying the liquid in the primary operation to produce a liquid enriched in another constituent and an effluent gaseous mixture, recompressing and returning the gaseous mixture for further liquefaction in the primary operation, subjecting the liquid produced in the primary operation to an auxiliary rectification with recompression and reliquefaction of the gaseous effluent and return thereof to the auxiliary rectification to separate a liquid product consisting of the principal constituent thereof and withdrawing a gaseous product from the auxiliary rectification consisting principally of the third constituent.

21. In an apparatus for analyzing ternary gaseous mixtures, the combination of primary and auxiliary rectification columns, means for conveying a liquid which is impoverished in one of the constituents of the mixture from the primary to the auxiliary rectifier, and means for returning a liquid which consists of another constituent in a substantially pure condition from the auxiliary to the primary rectifier.

22. In an apparatus for analyzing ternary gaseous mixtures, the combination of primary and auxiliary rectification columns, including means for liquefying gases in each of the columns, means for conveying a liquid which is impoverished in one of the constituents of the mixture from the primary to the auxiliary rectifier, and means for returning a liquid which consists of another constituent in a substantially pure condition from the auxiliary to the primary rectifier.

23. In an apparatus for analyzing ternary gaseous mixtures, the combination of primary and auxiliary rectification columns, means associated with the primary column for selectively liquefying the mixture, means for withdrawing the residual unliquefied constituent, means for conveying the liquid product of the primary column to the auxiliary column, means in the auxiliary column to separate the liquid into an effluent mixture and a liquid consisting of another constituent in a substantially pure condition, and means for returning the liquid product of the auxiliary column to the primary column.

24. In an apparatus for analyzing ternary gaseous mixtures, the combination of primary and auxiliary rectification columns, means associated with the primary column for selectively liquefying the mixture, means for withdrawing the residual unliquefied constituent, means for conveying the liquid product of the primary column to the auxiliary column, means in the

auxiliary column to separate the liquid into an effluent mixture and a liquid consisting of another constituent in a substantially pure condition, means associated with the auxiliary column to recompress and liquefy the effluent mixture, and means for returning the liquid product of the auxiliary column to the primary column.

25. In an apparatus for analyzing ternary gaseous mixtures, the combination of primary and auxiliary rectification columns, means associated with the primary rectification for selectively liquefying the mixture, means for withdrawing the residual unliquefied constituent, means for withdrawing an effluent mixture, recompressing and returning it to the primary column, means for conveying the liquid product of the primary column to the auxiliary column, means in the auxiliary column to separate the liquid into an effluent mixture and a liquid consisting of another constituent in a substantially pure condition, means associated with the auxiliary column to recompress and liquefy the effluent mixture produced therein, and means for returning the liquid product of the auxiliary column to the primary column.

26. In an apparatus for analyzing ternary gaseous mixtures, the combination of primary and auxiliary rectification columns, means associated with the primary rectification for selectively liquefying the mixture, means for withdrawing the re-

sidual unliquefied constituent, means for withdrawing an effluent mixture, recompressing and returning it to the primary column, means for conveying the liquid product of the primary column to the auxiliary column, means in the auxiliary column to separate the liquid into an effluent mixture and a liquid consisting of another constituent in a substantially pure condition, means associated with the auxiliary column to recompress and liquefy the effluent mixture produced therein, and means for returning the liquid product of the auxiliary column to the primary column.

27. A method of analyzing ternary gaseous mixtures, which comprises separating one of the constituents by a primary liquefaction and rectification operation, thereby providing a liquid consisting substantially of the remaining constituents, separating the latter constituents by an auxiliary rectification operation, returning one of the constituents in liquid form to assist in maintaining the necessary low temperature in the primary operation and evaporating the liquid returned by indirect contact with the gaseous mixture treated in the primary operation.

In testimony whereof I affix my signature.

CLAUDE C. VAN NUYS.
